BOWLING PIN HOLDING APPARATUS

Gottfried J. Schmidt, Pearl River, N. Y., assignor
to American Machine & Foundry Company, a
corporation of New Jersey

Application September 13, 1947, Serial No. 773,851

17 Claims. (Cl. 273—42)

1

This invention relates to bowling pin handling machines and more particularly to improvements in devices for engaging, gripping, and releasing bowling pins.

My invention is especially well adapted for use with a machine of the general type shown in my U. S. Patent 2,217,709, granted October 15, 1940, wherein a frame, which travels toward and away from the bed of a bowling alley is employed to carry bowling pin gripping devices. These pin gripping devices are constructed and arranged to grip standing bowling pins over which they have been centered due to the lowering of the frame. The gripped pins are then elevated by raising the frame to permit the fallen pins and bowling ball to be swept from the alley. The gripped pins are then lowered and replaced on the alley in the same position they occupied before being elevated.

It is an object of my invention to provide an improved light weight freely shiftable mechanical bowling pin gripping device.

Another object of my invention is to provide a light weight freely slidable pin gripping device which will have mechanical grippers that can maintain a holding grip on a pin without external assistance.

Another object of my invention is to provide a bowling pin gripping device which will have a toggle effect when the pin is held in gripped position so as to increase the gripping action in direct proportion to the weight of the gripped pin.

A further object is to provide a pin gripping device which will have the advantage that there will be no fluid or electrical connections between the supporting table and the gripping device.

Another object of my invention is to provide a bowling pin gripping device which will be locked against releasing a gripped pin when it is held in an elevated position above the alley.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

In the accompanying drawings:

Fig. 1 is a plan view of the improved pin gripper with portions broken away to show the pin gripping mechanism.

Fig. 2 is a front elevation of the improved bowling pin gripper taken on the line 2—2 of Fig. 1.

2

Fig. 3 is a sectional front elevation of the pin gripper supporting table in conjunction with the actuating mechanism for the pin grippers.

Fig. 4 is a plan view of the pin gripper supporting table in conjunction with a schematic wiring diagram of means for actuating the pin gripper mechanism.

My invention consists of a plurality of similarly constructed pin gripping devices equal in number 10 to the number of bowling pins used in a game of bowling. For purposes of illustration, I have shown this number to be ten in the present disclosure.

To illustrate an embodiment of my invention 15 I have shown one of these pin gripping devices in Figs. 1 and 2 which consists of a cone or camming skirt 10 and a pin receiving chamber 12. A tapered centering cup 14 is mounted for free up and down movement in this chamber and is 20 secured to a cover plate 16 by suitable means such as by a rivet 18. The cover plate 16 has three holes formed therein through which pins or studs 20 pass. The upward sliding movement of cover plate 16 is limited by heads 22 formed on 25 the pins 20. The pins 20 are slidably mounted in suitable holes formed in flange 24 of chamber 12 and pass through elongated slots 26 formed in the pivoted pin hinge plates 28 and also through holes formed in hinge supporting brackets 30 and, when pins 20 are depressed, through holes 32 formed in the upper portion of cone 10.

A collar 34 is fixedly mounted on each of the pins 20 and limits the extent to which the pins 20 can move upwardly by engaging with the underside of flange 24 as shown in Fig. 2. On 35 the lower end of each stud 20 is loosely mounted a sliding collar 36 against which spring 38 exerts downward pressure. The hinge plate 29 of each hinge is adjustably secured at one side to the bracket 30 by suitable screws 40. The other hinge plate 28 of each hinge has attached to it a suitable friction element 31 such as leather or rubber which engages directly with the upper part of the bowling pin handle P. The brackets 30 are 40 attached to the chamber 12 by suitable means such as screws 42.

The hinge plates 28 and 29 are pivotally connected by a pin 33. A torsion spring 27 is mounted on the pin 33 of each hinge to exert an upward spring tension pressure on hinge plates 28.

The cone shaped members 10 are slidably supported on a bottom plate 44 and are positioned over holes 46 formed therein which correspond in number and position to the arrangement of 45 bowling pins on a bowling alley.

The bottom plate 44 has four upwardly extending tubes 45 fixedly mounted near each corner of the bottom plate 44. Each tube 45 has a flange 52 formed at its upper end and is slidably mounted on a corresponding rod 48 which extends downwardly from the upper supporting plate 50.

The tubes 45 are pushed upwardly on the rods 48 by means of four bell crank levers 56 which have forked arms 54 which engage with the flanges 52. The lower end of each tube 45 has an air hole 47 which allows air to enter and escape from the tube 45 as the tube 45 travels up and down on the rod 48.

The bell crank levers 56 are pivotally mounted on supporting brackets 58 which are carried on the underside of the supporting plate 50 (Figs. 3 and 4). Also connected to the supporting plate 50 are four solenoids 60 which actuate the bell crank levers 56 when energized to decrease the distance between plates 44 and 50. A downward pressure is exerted on the tubes 45 by means of springs 49 to lower the bottom plate 44 when the solenoids 60 are deenergized.

Each of the brackets 58 carry studs 62 against which the bell crank lever arms 56 engage thereby limiting the extent of downward movement of the bottom plate 44. Attached to the top side of upper supporting plate 50 are supporting brackets 64 which have extending therefrom studs 66. The studs 66 are pivotally mounted in guide shoes 68 which slide up and down in the guide channels 70. The guide shoes 68 are lowered and raised in a manner similar to that shown in U. S. Patent 2,283,613 issued to me on May 19, 1942, by means of cables 72.

An electrical control cam 74 is provided to open and close a switch 76 which energizes and deenergizes the solenoids 60 through wires 77 and 79. Cam 74 and sprocket 80 are fixedly mounted on shaft 78. Driving motion is imparted to the sprocket 80 by means of chain 82 which is driven in proper timed relation with the operation of a pin setting machine such as that shown in U. S. Patent 2,298,718 issued to P. M. Nejedly on October 13, 1942.

The operation of my invention may be briefly described as follows:

After a bowling player has thrown his first ball, the pin gripper supporting plates 44 and 50 are lowered towards the bowling alley by means of cables 72. The heads of any standing pins which remain standing on the alley after the throwing of the first ball will pass through the circular openings 46 of the bottom plate 44. In passing through such circular openings 46 the heads of standing pins P engage with the sides of the respective cones 10 slidably supported over each hole 46. The various cones are thereby caused to shift laterally due to a camming action between the tapered camming skirt and the head of the bowling pin, until each has been centered over its respective standing pin.

When the cones have been approximately centered in the manner described, the continued downward movement of the platform or upper supporting plate 50 moves the chambers 12 relative to the tapered centering cups 14 and cover plates 16. The engagement of the pins with the cups 14 results in further centering of the cones 10 over the heads of the pins P. The relative movement between the centering cups 14 and the cones 10 allows for small differences in the length of bowling pins being used on the alley.

When the platform 50 has reached its lower-

most point of travel, switch 76 is actuated by the cam 74 to energize the solenoids 60. When the solenoids 60 are energized they pull in their respective plungers 84 thereby actuating the bell crank levers 56. The forked ends 54 of bell crank levers 56 engage the flanges 52 of tubes 45 thereby causing the lower plate 44 to be raised upwardly with respect to plate 50. This upward movement of the bottom plate 44 causes the button heads 22 to engage with the bottom of the platform 50. Continued upward movement of the plate 44 causes it to raise the cones 10 and chambers 12 relative to the centering cups 14 and pins 20. This relative movement causes the compression springs 38 to be compressed as shown in Fig. 3.

The rods or studs 20 extend downwardly through slotted openings 26, 32 and those formed in flange 24. The downward pressure exerted by the spring 38 on the sliding collar 36 causes the hinged gripping member 28 to descend until it engages with the handle of the bowling pin P. It will thus be seen that the cone is clamped between the bottom plate 44 and top plate 50 thereby causing the pin gripping members to be locked in gripping relationship.

The pin grippers are spaced from one another as shown in Figs. 1 and 4 so that when the table platform 50 is raised upwardly by means of cables 72, a toggle joint gripping action will be effected on the head of the bowling pin. The operative position of the grippers is such that the weight of the bowling pin P tends to move the grippers closer together, due to this toggle joint action and thereby increase the gripping action of the pin grippers 28 against the sides of the bowling pin handle P.

It will therefore be evident that I have provided a device for engaging, gripping, elevating and replacing bowling pins on a bowling alley which is not only lightly constructed but which effects a strong positive grip on the pins being lifted.

When the bowling pins are thus gripped and held in elevated position suitable sweeping mechanism such as shown in U. S. Patent 2,250,503, issued to R. E. Rundell on July 29, 1941, is employed for removing fallen bowling pins and the bowling ball from the bed of the bowling alley. After this sweeping operation has been completed cables 72 lower the platform 50 towards the alley. When the cables 72 have reached their lowermost point of travel, so that the bottoms of the gripped pins are touching the alley, the switch 76 is opened due to the rotation of cam 74 thereby deenergizing the solenoids 60. When the solenoids 60 are deenergized the flanges 52 under the downward pressure exerted by springs 49, are pushed downward thereby causing the lower plate 44 to descend out of engagement with the cones 10. The bell crank levers 56 come to rest against the pins 62 when the lower plate 44 has reached its lowermost point of travel and thereby limit the plate 44 from further downward movement.

As the bottom plate 44 is lowered it allows the springs 38 to expand pushing the cones 10 and chambers 12 downwardly. This in turn allows the hinge plates 28 carrying the pin gripping elements 31 to pivot upwardly under the action of springs 27 out of engagement with the bowling pins P. The tapered centering cups 14 and plates 16 will then be supporting the cones 10 and chambers 12 on the heads of the standing bowling pins.

As the top platform 50 is raised by cables 12, the bottom platform 44 engages with the cones 10 resting on the standing bowling pins P. The continued upward movement of the table platforms 50 and 44 raises the released pin gripping devices out of engagement with the standing bowling pins which will be left standing on the alley in exactly the same position they occupied before being lifted above the alley. Further upward movement of the platform 50 by means of cables 12 raises the lower platform 44 above the heads of the standing bowling pins.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. Apparatus for handling bowling pins comprising a platform movable towards and away from the bed of a bowling alley, said platform having a plurality of openings through which the heads and handles of standing bowling pins may pass, a planar member spaced above and extending across said platform, a plurality of shiftable members mounted above said openings for centering bowling pin grippers above a bowling pin, pivoted bowling pin grippers connected to said shiftable members for gripping the handles of standing bowling pins, projections extending upwardly from said pivoted grippers, mechanism for changing the distance between said planar member and platform to cause said projections to engage with said planar member to move said grippers into and out of gripping relationship.

2. Apparatus for handling bowling pins comprising a support, pin contacting members mounted for free horizontal movement on said support, spaced opposed pivoted pin holding plates mounted on each of said members, the pivots of the plates mounted on each member being so spaced that when the plates engage with a pin they are slightly inclined at an upward angle from the pivot to the portion of the plate which contacts the pin to provide a toggle joint gripping action on each bowling pin, means for bringing said plates into pin gripping relationship with the necks of standing bowling pins, and means for releasing said plates from pin gripping engagement with standing bowling pins.

3. Apparatus for gripping, lifting and replacing bowling pins on a bowling alley, comprising a platform support, mechanism for moving said platform support over a predetermined path of travel, members mounted for free horizontal movement on said platform support, said members having inclined pin contacting surfaces for centering said members over pins with which they are brought into engagement, a centering cup connected with each of said members for free vertical movement relative to said members when brought into engagement with the head of a bowling pin, pivoted pin gripper arms mounted in the upper end of said members for gripping the necks of bowling pins, said gripper arms being of a length and upward inclination such that the arms will have a toggle joint action when in engagement with the neck of a bowling pin and weighted thereby, gripper actuating elements extending from each of said grippers, a second supporting platform spaced from and mounted parallel to said first named supporting platform, and mechanism for moving one of said platforms

into and out of engagement with said elements to bring said grippers into and out of engagement with standing bowling pins.

4. Apparatus for engaging, gripping, lifting and replacing standing bowling pins on a bowling alley comprising, a platform having a plurality of openings for receiving the handles of standing bowling pins, freely shiftable cone-shaped members mounted above each of said openings, pivoted mechanical pin gripping devices mounted on top of each cone for engaging and gripping the handles of standing bowling pins, members extending upwardly from said cones for moving said grippers into pin gripping relationship each time said members are depressed, a common plate for engaging simultaneously with all of said members to control the actuation of said grippers, mechanism for raising and lowering said platform to lift and replace bowling pins on the bowling alley, and means for effecting relative movement between the plate and said members for depressing said members.

5. Apparatus for respotting standing bowling pins on a bowling alley comprising, a pair of spaced supporting plates, mechanism for moving said spaced supporting plates towards and away from the bed of a bowling alley to grip, elevate and replace standing bowling pins on a bowling alley, a plurality of cone-shaped freely shiftable pin gripping devices supported on the lower supporting plate, pivoted pin grippers mounted on each of said devices, upwardly extending members mounted on said devices which are constructed and arranged to move said grippers into gripping relationship each time said members are depressed, and mechanism for changing the distance between said supporting plates to bring the upper plate and said members into contact with each other to depress said members to lock said pin grippers about the necks of standing bowling pins.

6. Apparatus for engaging, gripping, lifting and replacing standing bowling pins on a bowling alley comprising, a support, a plate connected to and spaced from said support, said plate having a plurality of openings corresponding to the number of pins used in a game of bowling, a plurality of freely shiftable cones supported on said plate over each of said openings, a chamber having pin grippers located at the upper end of said cones, members projecting from said pin grippers for actuating said grippers to engage with standing bowling pins each time they are depressed, mechanism for lowering said support and plate to bring the cones into engagement with the standing bowling pins and thereby center each cone over the respective standing pins with which they engage, mechanism for changing the distance between said plate and said support after the cones have been centered over the standing bowling pins to bring the members and the support into contact to depress said members to lock said grippers about the standing bowling pins, and mechanism for returning said plate and said support to the original spaced relationship to release said pin grippers after the standing bowling pins have been replaced on the bowling alley.

7. Apparatus for gripping, lifting and replacing standing bowling pins on a bowling alley comprising a support, a plurality of cone-shaped members slidably positioned on said support and having pin engaging surfaces for centering each cone over a standing pin with which it engages, hinged members having elongated pin contact-

ing surfaces mounted on said cones for gripping bowling pins, projecting elements extending from said hinged members to move said hinged members into and out of engagement with bowling pins; a planar member adapted to engage all of said projecting elements of all of the cones simultaneously for controlling the pin gripping movement of said hinged members, means for lowering said support to center the pin grippers of each cone-shaped member over standing bowling pins, then lifting said support and gripped pins above the bowling alley to permit fallen pins to be removed from the bowling alley, and then lowering said support again to replace said gripped pins on the bowling alley, and mechanism for moving said elements into and out of engagement with said planar member to cause said pin grippers to be moved into and out of engagement with said standing bowling pins.

8. Apparatus for gripping bowling pins comprising, freely shiftable cone-shaped members, a common support for said cone-shaped members, hinged members mounted on said cone-shaped members and so spaced from each other on each cone and positioned at such an angle as to effect a toggle joint action therebetween when engaging with the handle of a bowling pin and subjected to the downward force exerted by the pin when it is lifted by said hinged members to increase the gripping force exerted by said hinged members, spring actuated means for normally maintaining said hinged pin gripping members out of engagement with standing bowling pins, members extending upwardly from said pin engaging members for bringing said pin engaging members into bowling pin gripping position, and a device for engaging and disengaging said upwardly extending members simultaneously at predetermined times to effect movement of said members and thereby bring said pin engaging members into and out of engagement with standing bowling pins.

9. Apparatus for gripping bowling pins comprising, freely shiftable cone-shaped members, a common support for said cone-shaped members, hinged members mounted on each cone-shaped member and so spaced from each other and positioned at such an angle as to effect an action therebetween when engaging with the handle of a bowling pin similar to a toggle joint whereby the pressure at the hinged joints increases as the pin exerts downward pressure at the area where said members contact said pins, spring actuated means for normally maintaining said hinged pin gripping members out of engagement with standing bowling pins, members extending from said pin engaging members for bringing said pin engaging members into bowling pin gripping position, and mechanism for depressing the members extending from said pin engaging members to move said pin engaging members into pin gripping position.

10. Apparatus for handling bowling pins comprising, a plate movable toward and away from the bed of a bowling alley for lifting gripped bowling pins above the bowling alley, a plurality of freely shiftable pin gripping devices supported on said plate, camming members for centering said pin gripping devices over standing bowling pins, pivoted members mounted in said devices and so spaced from each other and mounted at such an angle as to result in a toggle joint gripping force being exerted on a standing bowling pin by the downward pressure exerted by a gripped and lifted pin, mechanism for moving

5 said pivoted members into pin engaging position, and spring tension means for releasing said pivoted members from gripping action with the handle of a standing bowling pin.

11. Apparatus for handling bowling pins comprising, a support, mechanism for moving said support towards and away from the bed of a bowling alley on which bowling pins are standing, pivoted pin gripping members associated with said support, the pivots of said members being spaced equidistantly from a common center and the spacing of said pivots and the length of said pivoted members being such that the pivoted members will decline toward their pivots 15 when in engagement with a pin to thereby effect a toggle gripping action on the bowling pin when subjected to the weight thereof.

12. Apparatus for handling standing bowling pins comprising, devices having pin gripping 20 members, a pair of spaced, connected plates for supporting said pin gripping members, apparatus for changing the distance between said plates, a plurality of openings formed in the lowermost plate through which the heads of standing bowling pins may pass and come in contact with said devices, mechanism for moving said plates towards and away from the bed of a bowling alley, members projecting from said pin gripping members for moving said grippers into pin gripping relation, said members projecting a distance sufficient to be engaged and moved by the uppermost plate when the distance between said plates is changed to bring said pin grippers into pin gripping relation, and means for moving said 35 grippers out of gripping relationship.

13. Apparatus for handling standing bowling pins comprising, a frame having openings corresponding to the positions on a bowling alley on which bowling pins are spotted, apparatus for 40 moving said frame towards and away from the bed of a bowling alley to allow the heads of standing bowling pins to pass through said openings, a plurality of freely shiftable members having tapered walls positioned over each of said openings for engaging with the heads of standing bowling pins passing through said openings to approximately center said members over the standing pins, a centering device associated with the converging ends of said tapered walls for centering each of said members with respect to standing bowling pins, each of said centering devices having a predetermined free vertical movement relative to the shiftable members, spaced pin 45 engaging members for engaging at one end with the handle of a bowling pin, a pivot support for the other end of each of said pin engaging members, said pivot supports being so spaced and the members being of such length that when the members engage with the pin they are slightly 50 upwardly inclined from their pivots to the point of contact with a bowling pin and the downward force exerted by the pin on the members will tend to move all of said pin engaging members into straight line arrangement and thereby increase the gripping force exerted on the pin, and mechanism for holding said shiftable members fixed when said pin engaging members are in engagement with a standing bowling pin to positively hold said gripped bowling pin against relative movement with respect to said frame.

14. Apparatus for handling standing bowling pins comprising, a support, a frame carried by said support and having a plurality of openings corresponding to the positions on a bowling alley on which bowling pins are spotted, mechanism 55

for moving said support towards the bed of a bowling alley to allow the heads of standing bowling pins to pass through the openings formed in said frame, a plurality of freely slideable pin gripping devices mounted on said frame and support, tapered camming skirts associated with each of said pin gripper devices for engaging with the heads of standing bowling pins passing through said openings to slide a pin gripper device towards each standing bowling pin passing through said openings, a freely vertically reciprocable centering member associated with each of said pin gripper devices for centering the gripper device with respect to a standing bowling pin without raising the pin gripper device off the support, pivoted pin gripping members associated with said devices for engaging and gripping bowling pins, and pivot supports for each of said pin gripping members, said pivot supports being so spaced and the length of said pivoted members being such as to cause the members to incline downwardly toward the pivots when in engagement with the pin whereby the force exerted by the weight of the pin on the grippers is applied to the pin by means of a toggle action to effect a tighter grip on the pin.

15. Apparatus for handling standing bowling pins comprising, a support, pin gripping devices slidably mounted on and above said support, camming elements associated with said pin gripping devices for moving said pin gripping devices over the head of a standing bowling pin, a center cup freely movable vertically with each of said pin gripper devices to center the same with respect to a standing bowling pin while maintaining said pin gripping device free from elevation above said support by standing bowling pins, said pin gripper devices being constructed and arranged to grip when a downward force is exerted thereon by a bowling pin, and to release when the bowling pin is lifted upwardly, members extending upwardly from said pin gripping devices for moving said grippers into pin gripping relationship each time said members are depressed, a common plate for engaging simultaneously with all of said members to control the actuation of said grippers, mechanism for raising and lowering said platform to lift and replace bowling pins on the bowling alley, and means for effecting relative movement between the plate and said members for depressing said members.

16. Apparatus for handling standing bowling pins comprising, a platform having openings formed therein corresponding to the positions on a bowling alley on which bowling pins are spotted, pin gripping devices positioned over said openings, camming members associated with each of said pin gripping devices for moving a pin gripping device towards the head of each standing bowling pin, apparatus for moving said platform towards a bowling alley to bring said camming members into contact with the heads of standing

5 bowling pins, a loosely mounted centering device associated with said pin gripping devices for centering the devices with respect to said standing bowling pins without raising said gripping devices above said openings and to hold said bowling pins in position when engaged by said pin grippers, individual pin gripping fingers pivotally mounted at one end and spaced from each other a distance which will cause the opposite ends to support the weight of a pin by effecting a toggle joint hold on the pin, members extending upwardly from said pin gripping devices for moving said grippers into pin gripping relationship each time said members are depressed, a common plate for engaging simultaneously with all of said members to control the actuation of said grippers, mechanism for raising and lowering said platform to lift and replace bowling pins on the bowling alley, and means for effecting relative movement between the plate and said members for depressing said members.

17. Apparatus for engaging, gripping, lifting and replacing standing bowling pins on a bowling alley, comprising, a plate having a plurality 25 of holes corresponding to the number of bowling pins used in a game of bowling, a cone-shaped member slidably positioned over each of the holes of said plate for engaging, when lowered towards a bowling alley, with the heads of standing bowling pins to position the apices of said cones over the heads of standing bowling pins with which they engage, hinged bowling pin handle gripping arms mounted on each cone-shaped member, the arms mounted on each cone-shaped member facing to a common center and being of a length and upward inclination such that the arms will have a toggle joint action when engaging with the neck of a bowling pin and subjected to the weight of the pin, pin gripper actuating members 30 extending from each of said gripping arms, a gripper operating member, means for moving all of said gripper actuating members and said gripper operating members into contact with each other simultaneously to effect movement of 35 said gripper actuating members, and mechanism for moving said plate and cones towards and away from a bowling alley to bring said cones into and out of engagement with standing bowling pins.
